LUBRICATING SYSTEM

Philip A. Celander and Arthur C. Hollatz, Bloomington, Ill., assignors to Williams Oil-O-Matic Heating Corporation, Bloomington, Ill., a corporation of Illinois

Application January 2, 1935, Serial No. 14

5 Claims. (Cl. 184—18)

This invention relates to improvements in lubricating systems and more particularly to a system for automatically lubricating the pistons of a compressor.

5 It has been found that in the compressors employed in the compression type of refrigerating apparatus, which employ a splash system of lubrication, insufficient lubrication is provided for the pistons of the compressor, and it is an object 10 of this invention to provide a means actuated by the operation of the compressor to automatically lubricate the pistons of the compressor.

While the embodiment of this invention is illustrated and described in connection with a compressor employed in a closed system compression type of refrigerating apparatus, yet it may be applied as well to any type of compressor in which there is a differential in pressure between the high and low sides.

20 With these and other objects in view, reference is made to the accompanying sheets of drawings which illustrate preferred embodiments of this invention with the understanding that minor changes may be made without departing from the scope thereof.

25 In the drawings:

Figure 1 is a view in transverse central vertical section taken through a compressor employed in a closed system compression type refrigerating machine, with parts shown in elevation, illustrating a preferred form of this invention.

Figure 2 is a fragmentary enlarged detail view of the preferred form of automatic compression cylinder lubricating means, shown in Figure 1.

35 Figure 3 is a view in section taken on the line 3—3, Figure 2, looking in the direction of the arrows but omitting the showing of the cap means.

Figure 4 is a view in section taken on the line 4—4, Figure 1, looking in the direction of the arrows.

40 Figure 5 is a fragmentary view in section taken at right angles to Figure 1, illustrating a modified form of this invention.

Figure 6 is a view similar to Figure 5, illustrating the third form of this invention.

Figure 7 is a fragmentary sectional view taken on the line 4—4, Figure 1, illustrating an additional means for lubricating the wrist pin bearings of the connecting rods, with parts in elevation.

Figure 8 is a view in central vertical section through a piston showing said additional means for lubricating the wrist pin bearings.

55 In the form of this invention illustrated in Figure 1, the crank shaft 1 is mounted in suitable

bearings, not shown, in the crank case 2 with one end extending therethrough and provided with a pulley wheel 3 to be driven by a belt from an electric motor, or other means, not shown. A compression cylinder head 4 is preferably formed integral with the crank case upon the upper side thereof and the bottom of the crank case is shown provided with a removable cap 5. The eccentrics or cranks 6 of the shaft 1 mount the usual connecting rods 7 of the pistons 8. The 10 shaft bearings and the bearings of the connecting rods 7 upon the wrist pins are lubricated upon the rotation of the shaft by a bath of lubricant contained in the bottom of the crank case, as indicated upon the drawings.

15 In this embodiment, the gaseous refrigerant is compressed by the operation of the pistons and is expelled under compression through the top 9 of the cylinder head to be delivered through a pipe 10 to the high side of an evaporator or cooling unit, not shown. The low side of the evaporator or cooling unit is connected by a pipe 11 to the port 12 opening into the crank case 2 considerably above the level of the lubricant, all of which is usual construction.

20 In order to provide sufficient lubrication to the pistons reciprocating within the compressor 4, a pump cylinder is mounted upon the bottom of the cap 5, preferably centrally located thereon, to extend upward between the eccentrics or 25 cranks 6 of the shaft 1. As shown in Figures 1 and 2, the pump cylinder comprises a cylindrical casing 13 receiving within its lower end a plug 14 preferably threaded through an aperture provided therefor in the center of the cap 5. The 30 portion of the plug 14 entering the interior of the cap 5 is provided with a transverse port 15 communicating with an axial port 16 which passes upward through the body of the plug. The upper side of the plug within the cylinder casing 13 is 35 recessed and mounts a valve plate 17 adapted to reciprocate between the bottom of the recess and an abutment 18, preferably formed of a split ring engaged in a circumferential groove in the side walls of the recess. In one position the valve 40 plate 17 is adapted to seat over the axial port 16. It is preferable to provide the periphery of the valve plate 17 with a plurality of circumferential cutaway portions 19, as shown in Figure 3, to allow passage of fluid thereabout when the plate 45 45 is unseated. The upper end of the casing 13 is provided with a closure 20 which axially mounts a tube 21 depending therefrom and terminated a short distance above the recessed end of the plug 14. The pipe 21 communicates with an axial 50 50 55

recess 22 in the closure 20 which mounts a ball check valve 23. The axial recess 22 is provided with a closure 24 which axially mounts a pipe 25 communicating with the recess 22. The pipe 25 is extended through the crank case, preferably through a connection 26 provided at one side of the cap 5, which in turn is connected by the pipe 27 to a similar connection 28 threaded into the side of the cylinder head 4 intermediate the respective cylinders thereof to communicate with ports 29 extending through the walls thereof which in turn open into the interior of the cylinders below the piston rings of the pistons 8 in their lowermost position, and preferably arranged to be aligned with circumferential grooves 29^a upon the pistons when the pistons are at the end of their downward stroke.

When the compressor is first installed, the crank case is filled with lubricant to the proper level. The lubricant will enter through the ports 15 and 16 to unseat the valve plate 17 and enter within the casing 13 of the cylindrical pump cylinder until the pressure of the air entrapped therein above the level of the lubricant is equal to the pressure of the lubricant in the crank case above the level of the lubricant within said casing. Upon the initiation of operation of the compressor, the pressure within the crank case 2 is reduced and as the ports 29 are alternately uncovered by the pistons, the expansion of the air within the casing 13 of the cylindrical pumping member will cause the valve plate 17 to seat upon the axial port 16 and force the lubricant therein through the pipes 21, 25, and 27 to the ports 29 to deliver the lubricant to the grooves 29^a of the cylinders 8. In compressors employed for the purpose described, their operation is intermittent, and upon the cessation of operation the pressure within the crank case 2 will increase and thereby force the lubricant within the crank case 2 to enter the casing 13 of the lubricant pump to again compress the air therein, so that as soon as the exterior pressure is reduced, lubricant will again be fed to the cylinders.

Figure 5 illustrates a modified form of this device in which a metal disc 30 is mounted between the crank casing 2 and cap 5. The disc 30 is provided with a central opening 31 communicating with a chamber 32 provided upon the upper side thereof mounting a ball check 33 and communicating with the pipe 34 extending upwardly and about the eccentricities of the shaft 1 to enter into the web 35 between the cylinders in the cylinder head 4 to communicate with the transverse port 36 opening into the respective cylinders. The bottom of the cap 5 may be provided with a small central opening 37 which communicates with the interior of a metallic bellows 38 mounted upon the interior of the cap 5 concentric with the opening 37. The bellows 38 is closed at its upper end and is normally maintained in extended position by a spring 39 mounted upon the interior thereof. The metal disc 30 is provided with a port 40 and a flap valve 41 upon the under side thereof.

When the interior pressure of the crank case 2 increases, it will force lubricant through port 40 and past the valve 41 to compress the bellows 38, exhausting the air therein through the opening 37, so that as the pressure within the crank case 2 decreases, the flap valve will be closed and the lubricant entrapped by the valve below the disc 30 will be forced by the expansion of the spring-pressed bellows 38 through the chamber 32 and

pipe 34 to lubricate the pistons, as hereinbefore described.

Figure 6 illustrates another form of this invention which includes the mounting of a metallic bellows 42 upon a cylindrical base 43 formed upon the interior of the cap 5. The bellows is closed at its upper end and is normally maintained in extended position by a spring 44. The cap 5 is provided with a port 45 leading from the interior at one side of the bellows 42 and then extended upward to communicate with the interior of the bellows 42. This port is provided upon the interior of the cylindrical base within the bellows with a flap valve 46. The cap 5 is provided with another port 47 passing through the cylindrical base and leading from the interior of the bellows to a chamber 48, which chamber is provided with a flap valve 49 adapted to close said port 47. The chamber 48 communicates with a pipe 49^a passing through the lower end of the cap which is connected to the cylinder head 4 of the compressor in the manner shown in Figure 1.

Upon an increase in pressure within the crank case 2 the lubricant will be passed through the port 45 to the interior of the bellows 42 and compress the air entrapped therein until the pressures within and without the bellows are equal so that as the pressure within the crank case 2 decreases, the pressure of the air within the bellows will force the lubricant through the port 47, chamber 48, and pipe 49^a to lubricate the cylinders, as hereinbefore described, as the pressure within the crank case decreases.

If desired, the wrist pins 50 of the pistons 8 may be provided with an axial bore 51 adapted to open into the circumferential groove 29^a upon the piston 8. The bore 50 is provided with a central port 52 leading at right angles therefrom to the connecting rod bearing 53 about the wrist pins 50. By this means, each time the groove 29^a registers with the port 29 during operation of the pistons, then a part of the lubricant delivered from the crank case through the port 29 will enter the wrist pin bore 51 and be delivered through the port 52 to the connecting rod bearing 53.

From the above description, it is readily seen that by the provision of the lubricant pump within the crank case that during operation of the compressor, a simple and effective automatic lubricating means for the pistons and piston wrist pin bearings is actuated by the differential in the pressure upon the lubricant resulting from the operation of the compressor.

What we claim is:

1. A compressor for a closed system compression type refrigeration apparatus having a crank case containing a bath of lubricant, a lubricant pump for automatically lubricating the compressor pistons actuated by the decrease in pressure within the crank case resulting from the operation of the pistons, including a chamber closed at one end and a valved port at the other provided with a valve permitting lubricant to enter the chamber until the pressure of the air entrapped therein equals the pressure within the crank case when the compressor is idle, and means for delivering lubricant from the chamber to the piston cylinders upon a reduction of crank case pressure upon initiation of operation.

2. The structure of claim 1 wherein the said delivery means includes a pipe leading from the lubricant contained within the pump chamber provided with a check valve preventing the re-

turn of lubricant therefrom to the pump chamber.

3. The structure of claim 1 wherein the lubricant pump chamber includes a vertical cylindrical casing supported upon the bottom of the 5 crank case having said valved port adjacent the bottom thereof and wherein the said delivery means includes a pipe entering the casing and extending adjacent the bottom above the said valved port.

10 4. The structure of claim 1 wherein the said pump chamber includes a compressible metallic bellows mounted upon a base formed upon the crank case provided with a valved port leading from the interior of the bellows to the interior 15 of the crank case and with an additional port

leading from the interior of the bellows to the said delivery means.

5. The structure of claim 1 wherein each piston is provided with a circumferential groove below the piston rings arranged to receive the 5 lubricant delivered to the cylinder and wherein each wrist pin of each piston terminates within the circumference of the piston forming circumferential pockets traversing each circumferential piston groove and wherein each wrist pin is provided with a lubricating duct leading from said circumferential pockets to the bearing of the connecting rod upon the wrist pin. 10
